ATTORNEY

UNITED STATES PATENT OFFICE

WARREN W. SACKETT, OF MILWAUKEE, WISCONSIN, ASSIGNOR TO MILWAUKEE GAS SPECIALTY COMPANY, OF MILWAUKEE, WISCONSIN, A CORPORATION OF WISCONSIN

PROTECTING HOOD FOR CIGAR AND CIGARETTE LIGHTERS

Application filed October 28, 1931. Serial No. 571,527.

This invention relates to cigar lighters and has as an object to provide an enclosure for protecting the user against possible burns and to also protect the pilot flame against being extinguished by drafts.

Another object of this invention resides in the novel construction of the enclosing housing.

With the above and other objects in view which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing are illustrated two complete examples of the physical embodiment of the invention constructed according to the best modes so far devised for the practical application of the principles thereof, and in which:

Figure 1 is a side elevation of a cigar lighter constructed in accordance with this invention parts being broken away and in section to illustrate structural details.

Figure 2 is a developed view of one of the units of the enclosure; and

Figure 3 is a view similar to Figure 1 of a slightly modified form of this invention.

Referring now more particularly to the accompanying drawing in which like numerals designate like parts throughout the several views, the numeral 5 represents a valve casing which has a threaded inlet end 6 adapted for connection with a suitable fuel supply line, not shown, and a valve, not shown, adapted to be actuated upon depression of a plunger 7 to afford communication from the inlet end to the outlet end 8 of the casing, to which a tube 9 is attached.

The valve structure within the casing is of conventional design and is, therefore, not shown in detail, and as is customary in valves of this character, a by pass is provided to maintain a pilot flame at a burner tip 11, the volume of fuel which passes through the by pass being adjustable by a screw 10.

The tip 11 is fixed to the upper end of the tube 9 and upon depression of the plunger 7 and the consequent opening of the main valve, the volume of fuel flowing through the tube to the tip is suddenly greatly increased to produce a comparatively large flame at the tip 11.

Heretofore it has been customary to either leave the burner tip entirely open or to provide a shield which was intended to preclude the pilot flame from being extinguished by drafts. This shield, however, did not protect the user against possible burns and as very often the flame is of substantial proportions and suddenly flashes up, there is a considerable danger of the user being burned.

This invention contemplates the provision of a protecting enclosure which not only prevents drafts from extinguishing the pilot flame, but also entirely encloses the main flame during use. This protective housing comprises two similar hoods 12 and 13 spaced apart by an intermediate spacer 14. The hood 12 is carried by the tube 9 and is provided with a plurality of air inlet openings 15 in its bottom. The upper hood 13 also has a plurality of openings 16 in its closed top through which the exhaust gases are vented.

The intermediate spacer 14 comprises a cylindrical shell provided with an opening 17 of substantial diameter which affords access to the interior of the enclosure and through which the cigar or cigarette to be lit may be inserted. The opposite ends of the spacer 14 are preferably offset, as at 18, to be telescoped within the open ends of the hoods 12 and 13, and the spacer is preferably formed by cutting semi-circular notches in the ends of a flat strip as illustrated in Figure 2, so that upon forming the strip to cylindrical shape the notches come together and provide the opening 17.

If desired, a baffle 19 may be provided to further protect the pilot flame against being extinguished by a draft. This baffle, as illustrated in Figure 3, preferably comprises a cup shaped member whose cylindrical wall 20 is snugly received in the lower hood member 12 and whose transverse wall 21 is provided with a central opening 22 through

which the flame projects upon depression of the plunger.

From the foregoing description taken in connection with the accompanying drawing, it will be readily apparent to those skilled in the art to which an invention of the character described appertains, that the structure of this invention provides a simple, inexpensive but effective enclosure for cigar and cigarette lighters which not only protects the user against possible burns, but also guards the pilot flame and prevents its being extinguished by drafts.

What I claim as my invention is:

15. 1. In a cigar and cigarette lighter including a burner tip, an enclosure for a flame burning at the tip, comprising a pair of opposed hood members, one of which is supported from the burner tip, and a tubular spacer positioned between the hood members and having an opening through which a cigar or cigarette may be inserted for contact with the flame.
20. 2. A cigar and cigarette lighter comprising a burner tip, a support for the burner tip providing means for conducting fuel thereto, a protecting enclosure for a flame burning at the tip and comprising a cup shaped member carried by the support for the burner tip, a hood positioned above the cup shaped member and of substantially the same size in cross section as the cup shaped member, and a tubular spacer maintaining the cup shaped member and the hood spaced apart and having an opening through which a cigar or cigarette to be lit may be inserted for contact with the flame.
25. 3. A protecting enclosure for cigar and cigarette lighters comprising a pair of opposed open ended hoods of the same size in cross section, and a tubular spacer having its ends telescoped with the open ends of the hoods and having an opening through which a cigar or cigarette may be inserted into the enclosure.
30. 4. A protecting hood for cigar and cigarette lighters comprising two opposed cylindrical hoods having draft openings in their closed ends, and a cylindrical spacer sleeve having its ends telescopically connected with the open ends of the hoods and having an opening through which cigars and cigarettes to be lit may be inserted into the enclosure.
35. 5. A protecting hood for cigar and cigarette lighters comprising two opposed cylindrical hoods provided with ventilation openings in their closed ends, and a cylindrical spacer sleeve telescopically connected with the open ends of the hoods to maintain the same spaced apart, said spacer sleeve comprising a strip of bendable metal having its ends provided with semi-circular notches and maintained in cylindrical form with the notches adjacent to provide an opening to the protecting enclosure by the engagement of

the ends of the sleeve with the open ends of the hoods.

6. In a cigar and cigarette lighter including a burner tip and a support for the burner tip, a protecting enclosure for a flame burning at the tip comprising a pair of opposed hoods, one of which is carried by the support for the burner tip, a tubular spacer sleeve telescopically connected with the open ends of the hoods to maintain the same spaced apart and having an opening through which a cigar or cigarette to be lit may be inserted into the enclosure for contact with the flame, and a baffle extending across the hood carried by the burner tip support to provide additional protection for a pilot flame burning at the tip.

In testimony whereof, I have hereunto affixed my signature.

WARREN W. SACKETT.
